UNITED STATES PATENT OFFICE.

CHARLES A. MEUNIER, OF GREAT NECK, NEW YORK.

GUTTER HANGER.

Application filed December 14, 1926. Serial No. 154,784.

This invention relates to gutter hangers employed for the purpose of supporting gutters adjacent to the edges of roofs and the same has particular reference to an improved connection between the bridge and the suspension strap.

The invention comprehends a connection of the character set forth which eliminates riveting; which permits of the use of a bridge of narrower stock without detracting from the strength and which greatly simplifies and reduces the expense incident to establishing connection between the bridge and the suspension strap.

With the above recited and other objects in view reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a cross sectional view of a gutter and a portion of a roof with the improved gutter hanger in applied position;

Fig. 2 is a sectional plan view of the hanger on an enlarged scale taken approximately on the line 2—2 of Fig. 1;

Fig. 3 is a sectional bottom plan view of the hanger taken approximately on the line 3—3 of Fig. 1;

Fig. 4 is an enlarged fragmentary cross-sectional view taken approximately on the line 4—4 of Fig. 2;

Fig. 5 is an enlarged transverse sectional view taken approximately on the line 5—5 of Fig. 2;

Fig. 6 is a fragmentary perspective view of the lower end of the suspension strap prior to its attachment to the bridge.

Referring to the drawings by characters of reference, the hanger which is of the one-piece type, illustrated in my prior United States Letters Patent No. 1,572,745, granted February 9, 1926, includes the bridge portion 10 which is of substantially inverted U-shaped cross-sectional configuration having at one end the bendable extension 13 adapted to be trained around under the gutter to constitute a cradle and formed at the opposite end with a slotted terminal 14 to receive the free extremity of the extension or cradle.

The suspension strap 15 is notched at 16 at its lower end to provide a pair of furcations 17—17, which furcations are twisted a quarter turn from their normal position, 60 thereby engaging the notch 16 to conform to the external cross-sectional shape of the bridge piece 10. A channel-shaped clip 18 is seated against the under open side of the bridge piece 10 with the side flanges 19 embracing the lower portion of the bridge piece. At its medial portion the clip 18 is increased in width and is provided with slots 20 adapted to receive therethrough the lower ends of the furcations, which 70 lower ends or extremities 21 are bent upwardly to provide retaining claws which in addition to tightly drawing or impinging the upper end of the notched portion 16 into contact with the upper right portion of the bridge piece 10, clamps and binds the clip 18 in place. This forms a rigid locking connection between the suspension strap 15 and the bridge piece. It will be further noted that the twisted lower end 22 formed 80 at the juncture of the furcations with the main body of the strap, strengthens the strap at its weakest point and insures bending of the same at a point immediately above the notched lower end. 85

It will also be noted that a narrower gage of material for forming the hanger may be employed without detracting from the strength of the structure in that the claws or extremities 21 are bent outwardly instead of inwardly. 90

What is claimed is:

1. In a gutter hanger, a bridge piece of inverted U-shaped cross-sectional configuration, a suspension strap having a bifurcated lower end, the defining furcations twisted laterally outward to straddle the bridge piece, a slotted clip underlying the bridge piece, the slotted portions of which receive therethrough the furcations with the terminals of the furcations bent outwardly and upwardly to establish a rigid connection between the suspension strap and bridge piece. 95

2. In a gutter hanger, a bridge piece of channel construction having an opening at the lower side, a suspension strap having a bifurcated lower end, the furcations of which are twisted laterally a quarter turn and turned outwardly and upwardly to define locking claws, and a slotted clip underlying the bridge piece and having the claws engaged through the slotted portions thereof. 105 110

3. In a gutter hanger, a bridge piece of channel construction having an opening at the lower side, a suspension strap having a bifurcated lower end, the furcations of which are twisted laterally a quarter turn and turned outwardly and upwardly to define locking claws, and a slotted clip underlying the bridge piece and having the claws engaged through the slotted portions thereof, the twisted portion of the suspension strap at the juncture with the locking claws serving to strengthen the strap at the point of connection with the bridge piece whereby to insure bending of the strap at a point above the bifurcated lower end.
4. In a gutter hanger, an inverted channel-shaped bridge piece, a suspension strap, and means for establishing a rigid connection between the lower end of the suspension strap and the bridge piece, comprising a notched lower end of the gutter strap defining furcations laterally twisted outwardly and upwardly and bent to provide locking claws, and a channel-shaped slotted clip seated beneath said bridge piece, through the slotted portions of which the locking claws are engaged.
5. A connection between the suspension strap and bridge piece of a gutter hanger, comprising a bifurcated lower end of the suspension strap having laterally twisted outwardly and upwardly bent furcations, and a slotted clip underlying the bridge piece and receiving through the slotted portions thereof the laterally twisted outwardly and upwardly bent furcations.
6. A connection between the suspension strap and bridge piece of a gutter hanger, comprising a bifurcated lower end of the suspension strap having outwardly and upwardly bent furcations, and a slotted clip underlying the bridge piece and receiving therethrough the outwardly and upwardly bent furcations.
7. In a gutter hanger, including a gutter embracing element having a transverse bridge piece and a suspension strap, a means of connection between said suspension strap and bridge piece, comprising a bifurcated lower end of said suspension strap straddling the bridge piece, the furcation terminals being outwardly and upwardly bent, and a slotted clip underlying the bridge piece and receiving the outwardly and upwardly bent furcation terminals.
8. In a gutter hanger, including a gutter embracing element having a bridge piece disposed transversely of the upper open end of the gutter and a suspension strap; a means of connection between said suspension strap and bridge piece comprising a bifurcated lower end of said suspension strap straddling the bridge piece and defining furcations provided with outwardly and upwardly bent terminals; and a channel-shaped clip embracingly engaging the under portion of the bridge piece at its opposite ends, with a medial portion enlarged and slotted and receiving therethrough the outwardly and upwardly bent furcation terminals.

CHARLES A. MEUNIER.
